UNITED STATES PATENT OFFICE.

THEO. A. LUSK AND FRED HUEBNER, OF MILWAUKEE, WISCONSIN.

DESIGN FOR A FACE-PLATE AND FRAME FOR WEIGHING-SCALES.

SPECIFICATION forming part of Design No. 12,366, dated July 19, 1881.

Application filed May 24, 1881. Term of patent 7 years.

To all whom it may concern:

Be it known that we, THEO. A. LUSK and FRED HUEBNER, of Milwaukee, in the county of Milwaukee and State of Wisconsin, have 5 originated and invented a new and useful Design for a Face-Plate and Frame for Weighing-Scales; and we do hereby declare that the following is a full, clear, and exact description thereof, reference being had to the accompanying drawing, forming a part of this specification.

Our improved design for the face-plate and frame of weighing-scales is fully illustrated by the accompanying drawing, and its distinctive 15 features will be clearly set forth in the following specification and claims.

The face-plate A in our improved design is circular, and bears the usual graduation-marks on its outer edge, the longer or pound marks 20 extending to a ring, c, embossed in the metal. Inside of this ring, and between it and a smaller ring, c', are the pound numbers, and inside of this ring c' we produce a roughened or ground surface, relieved by concentric embossed rings 25 d d', and thus we produce a plate of very striking appearance and beauty, which we usually set in a frame, B, ornamented as follows: A circular rim, B, which we will call the "frame," is surmounted by a scarf, B', having a raised 30 border, and bearing the name of the manufacturer of the scale on its front, with an image of the Phoenix rising from its ashes surmounting the scarf. On its lower edge the rim B terminates in an ornamentation, B², 35 having a raised border, and designed to exhibit the name of the place of manufacture. Small ornamentations a a relieve each side of the rim B.

We claim—

1. In an improved design for the face-plates 40 of scales, the plate A, having embossed rings c c', and roughened or ground surface, as set forth.
2. In a design for the face-plate of scales, the embossed rings c c' d d' and roughened 45 surface inclosed by ring c', as set forth.
3. In an improved design for scale-plates and frame, the rim B, carrying scarf B', and ornamentation B², as set forth.
4. In an improved design for scale face- 50 plate and frame, as shown, a scarf supporting a Phoenix rising from its ashes.
5. A scale face-plate having scarf and Phoenix on top, side ornaments, a a, and bottom ornament, B². 55
6. The complete design for face-plate and frame of weighing-scales, consisting of the frame B, provided at its top with the scarf B', surmounted by a Phoenix rising from its ashes, and having bottom ornamentation, B², 60 and side ornaments, a a, dial-plate A, with embossed rings c c', with plain surfaces for the graduation-marks between its outer edge and the ring c, and for the numbers between the rings c c', and having embossed rings d d' 65 within the circle of ring c', relieved by a ground or roughened surface, all as described and shown.

In testimony that we claim the foregoing as our own we affix our signatures in presence of 70 two witnesses.

THEO. A. LUSK.
FRED HUEBNER.
